UNITED STATES PATENT OFFICE.

OWEN DAVID LUCAS, OF LINDEN GARDENS, LONDON, ENGLAND, ASSIGNOR TO V. M. L. EXPERIMENTAL LIMITED, OF WESTMINSTER, LONDON, ENGLAND, A BRITISH COMPANY.

SHELL.

Application filed June 20, 1922. Serial No. 569,732.

To all whom it may concern:

Be it known that I, OWEN DAVID LUCAS, a subject of the King of Great Britain, residing at 49 Linden Gardens, in the county 5 of London, England, have invented certain new and useful Improvements in or Relating to Shells, of which the following is a specification.

This invention relates to shells intended 10 to be projected into the air from an unrifled gun on the ground for signalling to or guiding aircraft by means for example of a light or smoke emitting device suspended from a parachute which, with the said device, is thrown from the shell by means of 15 an expelling charge, the said shell being made in three main parts, viz, a base, a nose or head and a connecting tubular body to which the base and the nose or head are connected in such a manner that when the expelling charge is ignited either the base or the nose or head will be forced off and the other of these two parts will remain connected to the tubular body.

20 According to the present invention the base or the nose whichever is intended to remain attached to the tubular body is connected to the latter by means of a portion of the body which is pressed or spun into 25 a circumferential recess in the base or the nose, and the nose or the base whichever is intended to be forced off by the expelling charge is connected to the body by one or more shearing pins; these means of connection are individually not new, and no claim 30 is made to them separately herein.

In order that the said invention may be clearly understood and readily carried into effect the same will now be described more 40 fully with reference to the accompanying drawings, in which:—

Figures 1 and 2 are respectively a side elevation and an axial section shewing one 45 form of the invention in connection with a shell of the parachute signal type.

Figures 3 and 4 are views similar to Figures 1 and 2 shewing a form of the invention in connection with a shell of the star or smoke pellet type.

50 Figure 5 is a section taken on the line 5, 5 of Figure 4.

Figure 6 is a section shewing the base of a shell provided with a modified form of igniting device.

Figures 7 and 8 are views similar to Figure 2 shewing two modified constructions of 55 parachute signal shells.

Figures 9 and 10 are views similar to Figures 4 and 5 shewing a modified construction of star or smoke pellet signal shell, and 60

Figure 11 is a view similar to Figure 8 shewing a modified form of the shell.

In each of the examples shown, A is the base, B is the nose or head and C is the tubular body which at one end 65 is pressed or spun into a circumferential recess in the base A or the nose or head B and at its other end is connected to the nose or head or to the base by small pins b— and bayonet slots c— there being for example three such pins and slots. D is the expelling charge and E is the Bickford fuse ignited by the igniting or fuse device. The pins b— are made of such diameter and material that when the bursting 70 charge is ignited they will be sheared and the body C will be left connected to the base A or to the nose or head B. F is a cup-shaped gas-check carried by the base A.

Referring to Figures 1 and 2, B¹ is the 80 parachute packed within the hollow nose B and C¹ is the container for the smoke or flame producing composition, which container is arranged within the tubular body C and is connected to the parachute by 85 means of a wire loop C² and a swivel C³. To the rear of the said container is a wood block C⁴ which is recessed at C⁵ to receive lead shot. This shot is intended to keep the total weight of the shell constant despite 90 differences in the weight of the container C¹ when loaded with different compositions the quantity of shot placed in the recess varying with such differences in weight. The container C¹ is separated from the parachute B¹ and from the wood block C⁴ by wads and washers as shewn. The rear part 95 of the said wood block is recessed to receive the expelling charge D which is ignited by means of the Bickford fuse E arranged in the base A. The composition in the container C¹ is ignited by a quick-match G. When the expelling charge D is ignited, the block C⁴ and the container C¹, are pressed forward and the nose B is forced 100 off through the intermediary of a wood ring C⁶, the pins b— being sheared during this 105 operation. The block, container and para-

chute are thus expelled and the block falls away thus leaving the container suspended by the parachute. The igniting device in this example is of the gas operated type and comprises a striker H mounted in a casing H¹ which is connected to the base A by a screw-threaded part h¹ and which carries a detonator cap h². The striker H is held in the retracted or safe position by a shear pin h and when the gun is fired the gases in the gun barrel operate upon the base of the striker (preferably through a small gas-check h^x) to force the striker against the detonator cap h². The flash 10 from this cap reaches the Bickford fuse through small holes in the casing H¹. The said cap is preferably the cap of a service rifle cartridge and the small gas-check h^x is preferably constituted by an empty cap 15 of this description.

The aforesaid gas-check F for the shell is connected to the base A by a nut F¹ screwed on the rear end of the casing H¹. This gas-check is made of thin metal and is 20 shaped as shown so that the gases in the gun barrel force the sides against the interior of the barrel, it being understood that the latter is as aforesaid unrifled. The recess for the Bickford fuse E is closed by 25 two washers E¹, E², against the rear one of which the base of the gas-check F bears.

Referring to Figures 3 to 5 K, K— represent the stars or smoke pellets which are packed within the tubular body C of the shell as shown in Figures 4 and 5 with primed paper discs k, k— between them. The arrangement of the igniting device and the gas-check F is similar to that described with reference to Figures 1 and 2 and the 30 flame from the Bickford fuse E is communicated to the expelling charge D (which in this case is situated in a recess in the front surface of the wood block C⁴) by means of strands of quick-match K¹ arranged as 35 shewn so that all the stars or pellets are properly lighted before the expelling charge is ignited. The portion of the quick-match passing through the wood block C⁴ and through the wad in front of this block is 40 covered by paraffined paper. In this construction of shell the nose of Figures 1 and 2 is replaced by a recessed disc B which is connected to the tubular body C by means of pins b— and bayonet slots c— in a 45 similar manner to that described with reference to the said nose so that this disc is blown out of the body when the expelling charge D is ignited, the stars or pellets being expelled from the body at the same time. 50 In order to facilitate the placing in position of the said disc the latter has a square projection B^x at its centre as shewn in Figure 4. The shell of Figures 3 to 5 is not intended to have a nose of similar contour 55 to that of Figures 1 and 2 although if de-

sired, such a nose, made of wood for example, might be attached to the disc B.

When a shell in accordance with my invention is intended for use at low altitudes the igniting device hereinbefore described 70 may be replaced by the arrangement shewn by Figure 6 in which the Bickford fuse E in the base A is ignited from the flame resulting from the ignition of the propelling charge in the gun when the latter is fired 75 the flash passing through the small hole f¹ in the nut F¹ and igniting a compressed powder pellet F² the flame from which passes to the Bickford fuse E, through a small hole f^x in a plug F^x screwed into the 80 base A.

In the construction shewn by Figure 7 the wood block C⁴ is formed on its front surface with a recess to receive the expelling charge D and the igniting device is a combination of the inertia type and the gas pressure operated type. In this case a detonator pellet h² is situated centrally in the rear part of the wood block and held in the inoperative position by means of a 90 shearing pin h^{2x} which is sheared by shock of discharge. The striker H carried by the gas-check F between which and the rear surface of the base A of the shell a detachable safety pin F⁰ is normally disposed. 95 The arrangement is such that on discharge the striker H is moved into its armed position by the movement of the gas-check F under the influence of the pressure of the gases in the gun barrel and the detonator 100 pellet h² then sets back on to the striker. The flash from the detonator is conducted to the aforesaid expelling charge by a Bickford fuse E which is suitably disposed in the wood block C⁴. 105

When as in Figure 8 the shell carries a parachute signal intended to be expelled from the rear of the shell, the parachute B¹ is disposed in a split wood cylinder B² arranged in the rear part of the tubular body 110 C and in front of this and resting in contact with the front surface of the said wood cylinder there is a split wood disc B³ through which the connection between the parachute and the composition container C¹ passes, 115 this container being situated between the said disc and felt and card discs arranged at the front end of the tubular body. In this arrangement of shell the expelling charge D is situated in a recess on the underside of 120 a metal disc B forming the lower part of the nose of the shell, the upper part B⁵ of which may conveniently be made of wood and between which and the said metal disc a felt washer B⁶ may be disposed. The igniting or fuse device in this construction is carried by the lower part of the nose and is of the inertia or set-back type comprising a detonator pellet h² normally held in its 125 inoperative position by a shearing pin h^{2x} 130

which on shock of discharge is sheared and the detonator brought into contact with a fixed firing needle or pin H. A detachable safety pin H^o may also be provided. The 5 flash from the detonator ignites a suitable length of Bickford fuse E communicating with the expelling charge D which serves to expel the parachute and the composition container from the rear of the shell (the 10 base being blown off during this operation as in this case it is more lightly attached to the tubular body than is the nose) and also to ignite the composition in the container C¹.

In the construction of star or smoke pellet 15 shell shewn by Figures 9 and 10, the stars or pellets K, K^o— are arranged end to end in separate tubes K², K² of which there may be three for example as shewn. These stars or pellets are ignited by quick-match leads 20 K¹ so arranged that the stars or pellets are ignited before they are ejected by charges (one of which is shewn at D^o) the star or pellet in each tube that is first ejected being ignited before the other in that tube. In this 25 construction the igniting device of Figure 6 is employed.

Figure 11 is similar to Figure 8 except that the needle or pin H sets back on shock of discharge and the pellet h² is fixed, and 30 that the parachute B¹ is arranged in front of the container C¹ and behind the expelling charge D the pressure from the explosion of which is transmitted to the container C¹ and the base member A without crushing the 35 parachute. A cavity between the base member A and a wood plug receives shot the quantity inserted being varied as required.

What I claim and desire to secure 40 by Letters Patent of the United States is:—

1. A shell comprising in combination a tubular body, a base member, a nose member, a portion of said body pressed into a circumferential groove in one of said members and a shearing pin connecting the other of said 45 members to said body, said pin engaging in a bayonet slot.

2. A shell comprising in combination a tubular body, a base member, a nose member, an expelling charge, a shearing pin for connecting one of said members to said body so 50 that this member will be blown off when the expelling charge explodes, said pin engaging in a bayonet slot, means for connecting the other of said members to said body

so that this member will remain connected 55 to said body when the expelling charge explodes and a cupped member carried by said base member to constitute a gas check.

3. A shell comprising in combination a tubular body, a base member, a nose member, 60 a portion of said body pressed into a circumferential groove in one of said members, a shearing pin connecting the other of said members to said body, said pin engaging in a bayonet slot and a cupped member carried by said base member to constitute a gas 65 check.

4. A shell comprising in combination a tubular body, a base member, a nose member, a portion of said body pressed into a circumferential groove in one of said members, 70 a shearing pin connecting the other of said members to said body, said pin engaging in a bayonet slot, an expelling charge and an inertia igniting device carried by said nose 75 member.

5. A shell comprising in combination a tubular body, a base member, a nose member, an expelling charge, a shearing pin for connecting one of said members to said body so 80 that this member will be blown off when the expelling charge explodes said pin engaging in a bayonet slot, means for connecting the other of said members to said body so that this member will remain connected to said 85 body when the expelling charge explodes, a cupped member carried by said base member to constitute a gas check, and an inertia igniting device carried by said nose member.

6. A shell comprising in combination a 90 tubular body, a base member, a nose member, a portion of said body pressed into a circumferential groove in one of said members, a shearing pin connecting the other of said members to said body, said pin engaging in a bayonet slot, a cupped member carried by 95 said base member to constitute a gas check, an expelling charge and an inertia igniting device carried by said nose member.

7. In a shell the combination with the elements claimed in claim 4, of a container for 100 a smoke or flame producing composition and a sustaining parachute for said container this parachute being arranged in front of said container and behind the expelling 105 charge.

OWEN DAVID LUCAS.
